UNITED STATES PATENT OFFICE.

RICHARD A. WHALL AND EUGENE R. BISHOP, OF ATHOL, MASSACHUSETTS.

LIGHT SCREEN FOR WINDSHIELDS.

Application filed April 17, 1922. Serial No. 554,171.

To all whom it may concern:

Be it known that we, RICHARD A. WHALL and EUGENE R. BISHOP, citizens of the United States, residing at Athol, in the county of 5 Worcester and State of Massachusetts, have invented new and useful Improvements in Light Screens for Windshields, of which the following is a specification.

This invention relates to a screen adapted 10 to be supported on the frame of the wind-shield of an automobile, in position to cover a portion of the glass of the wind-shield between the driver's eyes, and a source of light such as the sun, or the headlights of 15 an approaching automobile, and thus prevent interference with the driver's vision by glaring light rays shining directly on his eyes.

The object of the invention is to provide 20 a neat and attractive screen of simple and inexpensive construction, adapted to be engaged in different positions with a wind-shield frame, and to remain in any position to which it may be adjusted.

25 The invention is embodied in the improvements which we will now proceed to describe and claim.

Of the accompanying drawings forming 30 a part of this specification,—

Figure 1 is a perspective view of a screen embodying the invention, portions of the body sheet being broken away.

Figure 2 is a section on line 2—2 of Figure 1, and a sectional view of a portion of 35 a wind-shield.

Figure 3 is a section on line 3—3 of Figure 1.

Figure 4 is a plan view of the blank from 40 which the body sheet and the hook sheaths are made.

The same reference characters indicate the same parts in all of the figures.

Our improved screen includes a substantially U-shaped frame composed of a length 45 of wire bent to form a transverse neck portion 12, two substantially parallel spaced apart arm portions 13, connected by the neck portion, and hooks 14 at the outer ends of the arm portions. The portions 12 and 13 partially bound a space which is filled 50 by a body sheet 15 of any suitable sheet material, such as enameled cloth, marginally secured to said portions, preferably as hereinafter described. The hooks 14 are covered 55 by pocketed sheaths 16, which are preferably of the same material as the body member,

and integral therewith, said sheaths concealing the hooks 14 and presenting yielding inner surfaces, adapted to frictionally engage portions of the upper horizontal member 17 of the frame of a wind-shield, and permit the screen to be adjusted by sliding it edgewise along said member, the frictional engagement retaining the screen in any position to which it may be adjusted. 60 In practice the screen is hung with its body sheet 15 at the front side of the wind-shield.

The body sheet 15 and sheaths 16 are preferably formed from a blank of the contour shown by Figure 4, said blanks having a 70 transverse flap 15^a at one end, longitudinal flaps 15^b at its opposite longitudinal edges, and spaced apart sheath-forming extensions at its opposite end, said extensions including portions of the flaps 15^b. The flap 15^a is folded over the transverse neck portion 12 of the frame, the flaps 15^b are folded over the arm portions 13, and the extensions are folded over the hooks 14, the edges of said extensions meeting at the inner sides of the 75 hooks. The flaps are secured to the body sheet 15, and the meeting edges of the extensions are secured to each other, by stitches 18 arranged as shown by Figure 1, so that pockets are formed entirely enclosing the 80 frame portions 12 and 13 and the hooks 14. The wire of which the frame and hooks are composed is therefore entirely concealed and the hooks are prevented from contacting 85 with and sliding loosely on the top member 17 of the wind-shield frame.

We preferably provide a finishing flap 15^c at the end of the body sheet between the extensions, and fold the same against the body sheet, and secure it by stitches 19, thus forming a finished folded transverse edge 20. A mirror 21, shown by dotted lines in Figure 2, may be attached to the inner side of 90 the body sheet to enable the driver to see reflections of objects behind his vehicle. 95

The operation of folding the flaps 15^a and 15^b over the neck portion 12 and the arm portions 13, forms finished folded edges at the outer sides of said portions, so that the body sheet 15 presents four finished folded edges, three of which are formed by folding the flaps 15^a and 15^b and the fourth by folding the flap 15^c. Said folded edges impart a neat appearance to the screen, the raw or cut edges of the material being concealed excepting at the inner edges of the sheaths. The form of the body sheet is 100 105 110

such that the quantity of material required therefor, is reduced to a minimum.

We claim:

A light screen adapted to be suspended and moved edgewise on the top member of a wind-shield frame and comprising a substantially U-shaped metal frame, the upright parallel members of which terminate in hooks, and a flexible body sheet having top, bottom and side flaps, the side flaps being folded about the upright members of the frame and secured to the body of the sheet with their upper ends extending beyond the

upper edge of the body sheet and folded and secured about the hooks on the frame, the bottom flap of the body sheet being folded and secured about the bottom frame member and the upper edge flap of the sheet extending between the side flaps and being folded and secured directly against the body of the sheet, as and for the purpose described.

In testimony whereof we have affixed our signatures.

RICHARD A. WHALL.
EUGENE R. BISHOP.
